UNITED STATES PATENT OFFICE.

HARVE R. STUART, OF WHEELING, WEST VIRGINIA.
MAGNET FOR TELEGRAPHONES.

No. 902,773.

Specification of Letters Patent.

Patented Nov. 3, 1908.

Application filed March 2, 1908. Serial No. 418,691.

To all whom it may concern:

Be it known that I, HARVE R. STUART, a citizen of the United States, residing at Wheeling, in the county of Ohio and State of West Virginia, have invented certain new and useful Improvements in Magnets for Telegraphones, of which the following is a full, clear, and exact description.

This invention relates to telephones, 10 and has special reference to the electromagnet which is used for recording and reproducing the speech, message or signal.

In the well known form of telephone, 15 the electromagnet is an ordinary coil wound upon a solid iron core, the pole of which is presented to the steel wire or other recording body. The frictional contact between the pole which is of soft iron and the recording body results in rapid wear of the pole 20 piece which requires frequent renewals. It has heretofore been proposed also to substitute for the ordinary type of electromagnet a solenoid through the axis of which the recording body in the form of a wire moves. 25 So far as known to me, however, the solenoid has not been practically used in connection with the telephone, the reason being that a number of difficulties are encountered, particularly in that it is difficult to concentrate 30 all of the lines of force upon the recording body. The present invention is designed to overcome some of these difficulties, and also to prevent undue wear of those parts of the magnet which come in contact with the 35 traveling wire. My invention consists in so shaping the magnetic circuit of the solenoid that the lines of force thereof will be concentrated upon the wire, and in the provision of a bearing composed of refractory material, such as a jewel, interposed in such a 40 way as to prevent the wire from running in contact with the soft iron parts of the magnet.

In the accompanying drawing: Figure 1 is a side elevation of one form of my invention; Fig. 2 is a sectional view thereof; Fig. 3 is an end elevation; Fig. 4 is a sectional view of another form of my invention; and Fig. 5 is an end elevation thereof.

In the form of my invention illustrated in 50 Figs. 1, 2 and 3, 1 indicates a cylindrical block of non-magnetic material, provided with a circumferential deep and narrow groove forming a winding space for an electric coil 2. Channels 3 are provided for the 55 terminals of the coil which protect them

from injury, and may lead to binding posts fixed to any part of the block 1 (not, however, shown in the drawing), or to any other point where the terminals are to be mechanically fixed. At the axis of the cylindrical 60 block there is a longitudinal passage 4, through which the recording wire of the telephone, indicated by the dotted line in Fig. 2, passes. This cylindrical block is in effect a spool which together with the coil 2 65 constitutes an ordinary solenoid, the magnetic circuit of which would ordinarily be through the air. In order, however, to concentrate the lines of force and provide a magnetic circuit of comparatively low re- 70 luctance, I provide the soft iron disk 5, which has two spring clips 6, by means of which it can be slipped over one end of the block 1 and held in position thereon. This disk has a central hole 7, in line with the passage 4 75 of the block to accommodate the recording wire. The head of the spool against which the disk is placed is made as thin as possible so as to bring the disk close to the winding and thus shorten the magnetic circuit. The 80 lines of force are thereby concentrated upon that part of the wire which is inclosed in the opening 7 of the disk. In this construction, the block 1 may be made of tough or wear-resistive material so that the friction of 85 the wire moving through the axial passage will not result in cutting into the disk, the wear being taken by the block inside of the disk.

In Figs. 4 and 5, the preferred form of 90 my invention is illustrated. In this case the solenoid, which may be comparatively longer, has two soft iron heads 8 and 9, corresponding to the disk 5 in Figs. 1, 2 and 3, and these heads instead of being flat disks are shaped 95 to enter the interior space of the winding, the two disks approaching each other until they are separated by only a short space at the center of the winding. In this separating space a small collar of brass, or a perforated 100 jewel 10, is inserted and held in an axial position. The opening in the jewel is in line with the axial openings in the disks 8 and 9 to form the passage for the moving recording wire, the opening in the jewel being of 105 slightly less diameter than those in the disks so as to entirely prevent contact between the wire and the soft iron. In this construction, the lines of force are concentrated upon that portion of the wire within the passage. In 110

either of the constructions herein described the coil space may receive one or more windings for the usual purposes of recording, reproducing and erasing the record.

5. What I claim, is:—

1. In a telegraphone, a recording magnet in the form of a solenoid, a record medium adapted to move through the solenoid, and iron masses entering the solenoid at each end 10 but separated by a space less than the length of the solenoid.
2. In a telegraphone, a recording magnet in the form of a solenoid, a record medium adapted to move through the solenoid, said 15 solenoid having iron heads shaped to enter the interior space of the solenoid but separated therein by an air space.
3. In a telegraphone, a recording magnet in the form of a solenoid in combination with 20 a recording wire passing axially through the same, and a bearing for said wire composed of wear-resistive material and located adjacent to the solenoid.
4. In a telegraphone, a recording magnet 25 in the form of a solenoid in combination with a recording wire passing axially through the same, and a bearing for said wire composed

of wear-resistive material and located inside the solenoid.

5. In a telegraphone, an electromagnet in 30 the form of a solenoid, a part of whose magnetic circuit is formed of iron, said iron part being provided with an opening through which the recording body passes, and a bearing of wear-resistive material for the wire. 35

6. In a telegraphone, an electromagnet in the form of a solenoid provided with axially arranged iron disks at each end constituting a part of the magnetic circuit of the solenoid, and a bearing of wear-resistive material for 40 the recording wire and located between said disks.

7. In a telegraphone, an electromagnet in the form of a solenoid having iron heads shaped to enter the interior space of the 45 solenoid winding, and a perforated jewel confined axially between said heads.

In witness whereof, I subscribe my signature, in the presence of two witnesses.

HARVE R. STUART.
